UNITED STATES PATENT OFFICE.

ARCHIE NAULT, OF PORTLAND, OREGON.

STEAM BOILER.

Application filed October 25, 1922. Serial No. 596,879.

To all whom it may concern:

Be it known that I, ARCHIE NAULT, a citizen of the United States of America, and resident of the city of Portland, in Multnomah County, State of Oregon, have invented certain new and useful Improvements in Steam Boilers, of which the following is a specification.

My invention relates to steam boilers and particularly to an internally fired type of steam boilers provided with a peculiar arrangement of both water and smoke flues.

One object of my invention is to provide a type of boiler construction in which greater economy in the use of fuel may be had by extracting therefrom a larger percentage of the heat units developed by burning, and one which shall be compact in shape, of a type of construction which is readily manufactured and to which repairs may be readily made.

The features of my invention which I believe to be new and upon which I desire to secure a patent will be hereinafter described and then particularly defined by the claims.

In the accompanying drawings I have shown my invention embodied in a type of construction which I prefer to use.

Figure 1 is a transverse section taken substantially upon the plane indicated by the broken line 1, 1 of Figure 2.

Figure 2 is a longitudinal section taken on the vertical plane passing through the center line of the boiler.

Figure 3 is an outer end view of the boiler with the outer casing of one smoke chamber in section.

Figure 4 is a detail showing the manner of inserting and securing certain of the flues in the boiler.

The boiler illustrated in the drawings has an inner and outer shell forming between them water containing spaces, which spaces extend over the head of the inner shell as well as about its periphery. These water spaces extend downward at the under side of the boiler to form a water leg as 10 in which is placed the grate 11. At one end of the furnace chamber thus provided, a suitable fire door or doors 12 are provided.

The inner shell 1 above referred to and the outer shell 2 are preferably made concentric with each other, the inner shell being enough shorter than the outer shell to

form a suitable water space as 12 between the two heads at each end of the boiler. The

shell 2 which I have above referred to as the outer shell, is in reality an intermediate shell, if the shell 3 which encloses the smoke passages is considered. This last, which is the outermost shell, forms a smoke passage 30 extending about the periphery of the shell 2 and has its heads 31 and 32 spaced away from the heads of the shell 2 a sufficient distance to form smoke flues. One of these heads is connected with a stack flue 33 from which the products of combustion are conveyed away from the boiler.

Centrally positioned within the inner shell 1 is a water drum 4 which drum extends from head to head of the inner shell. Extending in a general radial direction from this drum 4 to the periphery of the inner shell 1, are a series of flues or pipes 40 which form water connection between the interior of the drum 4 and the water space 20 between the inner and next outer or intermediate shell 2. These radially positioned flues 40 are spaced at intervals in the upper half of the circle of the boiler. They are arranged in rows which extend lengthwise of the axis of the boiler. In one of the lower quarters of the boiler a baffle wall 42 is provided which extends across the space between the drum 4 and the inner shell 1. This causes the gases of combustion to be deflected to the other side of the boiler and to pass in a circular path about the central drum 4. Just above the baffle wall 42 are a series of flues 43 which extend across the water chamber 20 between the inner and the intermediate shells connecting the main annular chamber within the inner shell with the smoke passage 30 which lies between the intermediate shell 2 and the outermost shell 3. The gases of combustion after passing about the drum 4 pass through the flues 43 into the smoke chamber 30 and thence pass about the periphery of the boiler between the two shells 2 and 3 until the opposite end of the chamber 30 is reached. At this point a port or opening 34 is left in one of the partitions 35 which separates the peripheral section of the smoke chamber, represented by the passage 30, from the chambers 36 and 37 which lie between the head of the intermediate shell 2 and the outermost shell 31 and 32. The gases of combustion pass into the chamber 37 which is at the forward head of the boiler.

The heads 22 of the intermediate shell, being the outer head of the boiler proper, are

- provided with openings for the reception of flues which extend from head to head. Of these flues a certain number, 5, located so as to pass through the central drum 4, are secured directly into the heads 21 at opposite ends of the boiler. These form flues for the passage of the hot gases from the chamber 37 at one end of the boiler to the corresponding chamber 36 at the other end. 10 From thence they pass into the uptake or stack 33. There are similar flues 41 which connect the heads of the inner shell and which lie within the segments between the radial flues 40.
- 15 The heads 22 of the intermediate shell are provided with openings alined with the flues 41 and of a size to permit passage of these flues so that the same may be removed, inserted, and other repair work be conveniently done thereon. The holes in the heads 22 are closed by means of a cup-like member 6 which is made of metal and has a shallow cup, this being of a size to fit snugly in the hole in the head 22. It is secured in place by rolling, after the manner in which boiler flues are secured in the heads. This is clearly indicated in Figure 4.
- 20 In connection with the flues 41 which contain water, I prefer to employ smaller smoke flues as 60 which have their ends similarly secured in the bottom of the cup member 6 by being rolled in holes centrally formed therein, as is clearly indicated in Figure 4. These pass concentrically through the water containing flues 41 and connect the heads 22 of the intermediate shell 2. These form additional passages for the passage of gases of combustion between the two head chambers 36 and 37. If at any time it is necessary to repair either of the tubes 41 or 60, the cup member 6 may be removed along with one of the inner flues 60. The other flue 41 may then be similarly removed, following the method of procedure adopted in 25 removing boiler flues.
- 25 I may also provide fire tubes 61 connecting the heads of the outer boiler shell 2 and extending through the annular water-holding space between inner and outer boiler shells 1 and 2.
- 30 It will be noted that all parts of the above boiler are strengthened against strains in every direction. It is also possible to get at the flues and tubes employed to remove or repair them. The outer shell or jacket 3 which encloses the gas flues, may be readily removed for access to the shell of the boiler proper. In consequence of the large surfaces which are exposed to the action of the 35 gases, the evaporation per unit of fuel will be large. The boiler will therefore be economical in operation. It is also compact and well adapted for any purpose such, for instance, as marine work, where capacity and economy of space are important items.

While the boiler herein described has been referred to as a steam boiler it is evident that it may be employed as a boiler for hot water heating systems.

What I claim as my invention is:

1. A boiler comprising two concentric shells differing in length and each including a cylindrical major part having depending sides and heads connected at their lower edges to form water legs and an enclosed furnace chamber, a centrally placed water drum connecting the heads of the inner shell, radially positioned water pipes extending between the cylindrical portions of said drum and the inner shell and connecting the interior of said drum with the water space between the two shells, a baffle extending between the drum and the first shell over one side of the furnace chamber and smoke flues connecting the two shells closely above said baffle. 70

2. A boiler comprising two concentric shells differing in length and each including a cylindrical major part having depending sides and heads connected at their lower edges to form water legs and an enclosed furnace chamber, a centrally placed water drum connecting the heads of the inner shell, radially positioned water pipes extending between the cylindrical portions of said drum and the inner shell and connecting the interior of said drum with the water space between the two shells, a baffle extending between the drum and the first shell over one side of the furnace chamber, smoke flues connecting the two shells closely above said baffle, an outer casing forming smoke boxes at each end of the boiler and a chamber extending peripherally over the cylindrical part of the boiler, one of said smoke boxes being connected with said peripherally extending chamber at one end of the latter, a stack connected with the other smoke box and smoke flues extending between opposite heads of the outer boiler shell. 90

3. A boiler having inner and outer cylindrical shells and heads therefor forming an annular water space between them and extending between their heads, a centrally placed water drum connecting the heads of the inner of said shells, smoke flues passing through said water drum and connecting the heads of the outer of said shells, a third and outermost shell enclosing the two first named shells and spaced therefrom to form smoke passages about their periphery and over their heads, partitions dividing said smoke passages at the outer periphery of the boiler heads, one of said partitions having a communicating opening in the lower quarter thereof, a baffle connecting the inner shell with the central water drum on the opposite lower quarter, smoke flues just above said baffle extending through the water space between the two 100

inner shells, smoke flues connecting opposite heads of the outer boiler shell and extending through the inner shell outwardly of the central drum, and a discharge connection with the smoke chamber at the end opposite that which is connected with the peripheral smoke passage.

4. A boiler having an inner and an outer shell and heads therefor forming an annular water chamber and communicating chambers extending over the heads, and a third shell enclosing the boiler shells and forming smoke passages enveloping the first named shells, the head and peripheral portions of said smoke passages being separated by partitions one of which has a flue opening at one lower quarter of the boiler, smoke flues connecting the peripheral smoke passage through the water chamber with the interior of the inner shell in

the lower quarter opposite to that containing the said flue opening, a central water drum connecting the heads of the inner drum, a baffle extending across the combustion chamber lying between said drum and the inner boiler shell and located just below the smoke flues which connect said combustion chamber with the peripheral smoke chamber, smoke flues connecting the heads of the outer boiler shell through the central water drum, radially extending pipes connecting said central drum with the periphery of the inner shell across the combustion chamber, and water tubes connecting the heads of the inner shell and extending through said combustion chamber between said radial flues.

Signed at Portland, Multnomah County, Oregon, this 14th day of October 1922.

ARCHIE NAULT.
